UNITED STATES PATENT OFFICE.

RUDOLF E. HELLMUND, OF SWISSVALE, AND CHARLES W. STARKER, OF PITTSBURGH, PENNSYLVANIA, ASSIGNORS TO WESTINGHOUSE ELECTRIC AND MANUFACTURING COMPANY, A CORPORATION OF PENNSYLVANIA.

DYNAMO-ELECTRIC MACHINE.

1,305,102.

Specification of Letters Patent. Patented May 27, 1919.

Application filed October 14, 1916. Serial No. 125,587.

To all whom it may concern:

Be it known that we, RUDOLF E. HELLMUND, a subject of the German Emperor, and a resident of Swissvale, in the county 5 of Allegheny and State of Pennsylvania, and CHARLES W. STARKER, a subject of the German Emperor, and a resident of Pittsburgh, in the county of Allegheny and State of Pennsylvania, have invented a new and 10 useful Improvement in Dynamo-Electric Machines, of which the following is a specification.

Our invention relates to dynamo-electric machines and especially to certain structural 15 features of frames for electric railway motors and the like.

One object of our invention is to provide relatively simple and inexpensive means for permitting a variation of certain important 20 frame dimensions, while utilizing standardized parts and without requiring a varied setting of manufacturing machines.

More specifically stated, it is an object of our invention to provide a dynamo-electric 25 machine frame having a gap in one side provided with parallel - outwardly - extending lips for receiving and supporting an axle-bracket, the length of the lips being selected to procure any desired distance between the 30 "center" of the motor frame and the axle-bracket position.

Our invention may best be understood by reference to the accompanying drawings, wherein Figure 1 is a view, in end elevation, 35 with parts broken away for clearness, of a dynamo-electric machine frame embodying our invention; Fig. 2 is a view, in side elevation, of the structure that is shown in Fig. 1; and Fig. 3 and Fig. 4 are detail views 40 taken at right angles, the one to the other, of a certain portion of the frame that is illustrated in Fig. 1.

Referring to the drawings, the structure shown comprises a main magnetizable yoke 45 or band member 1, preferably of the illustrated customary polygonal shape, having a gap or opening 2 (best shown in Fig. 3 and Fig. 4) in one side that is provided with parallel, outwardly-extending lips 3 and 4 of a length that is selected to meet the desired conditions, as more fully set forth later. An axle-bracket seat member 5 of approximately semi-cylindrical form, is lo-

cated in such manner as to mechanically and magnetizably bridge the gap 2 for the purpose of supporting the customary axle 55 bracket (not shown), as subsequently described in detail.

A pair of end-members, which may take the form of rings 6 and 7, are spaced suitable distances apart from the main yoke 60 member 1 and are mechanically secured thereto through the agency of the axle-bracket seat 5, a plurality of tie-pieces 8, and a suspension bar 9, as about to be set forth fully.

The axle-bracket seat member 5 preferably is of a length greater than the over-all dimension of the remainder of the motor frame, as clearly shown in Fig. 2, and comprises an approximately semi-cylindrical intermediate portion 11 and right-angled end-projections 12 and 13 which respectively abut against the ends of the outwardly-extending lips 3 and 4 of the main yoke member 1. The lips 3 and 4 are provided with 75 a suitable number of holes or apertures 14 through which extend rivets 15 for the purpose of securing the longitudinal central portion of the seat member 5 to the yoke member.

In the process of manufacture of the main yoke member 1, the dies, which are employed in presses to suitably shape the yoke member from a flat bar, may be utilized to produce yoke members having any desired 80 length of lips 3 and 4, merely by suitably selecting the initial length of the bar in question. Thus, the same dies may be employed to provide the main yoke member 1, as illustrated in solid lines, or a corresponding yoke member having longer lips, as indicated by the dotted extensions 16 and 17 of the present lips 3 and 4. The same axle-bracket seat member 5 may be secured to the lips of whatever length, as indicated by the dotted 85 structures 18, 19 and 20, which respectively correspond to the solid line members 11, 12 and 13.

The purpose of varying the length of the lips 3 and 4 is to procure the desired distance between the "center" of the motor frame and the axle-bracket position, or, in other words, to vary the "gear-center-distance" of a railway motor, that is to say, the distance between the armature shaft and

the center of the driven gear wheel that is usually employed in connection with railway motors.

As is well-known, it is desirable to provide means for varying the above-mentioned "gear-center-distance" to meet certain operating conditions which it is not necessary to discuss in detail here, and our present invention provides a simple and inexpensive 10 method for supplying such needs. As previously stated, the same dies may be employed to produce yoke members having any length whatever of lips, corresponding to the illustrated members 3 and 4, and such 15 lips may then be readily machined to the exact length desired and drilled at the proper points to receive the rivets or equivalent connecting members 15.

Thus, in the case illustrated by Fig. 1, the 20 "gear-center-distance", corresponding to the axle-bracket seat 5 and the lips 3 and 4, is OC1 where O represents the "center" of the motor frame, that is, a point in the center of the armature shaft (not shown) and C1 25 represents a point in the center of the driven truck-axle, as will be understood. The line OC2 represents the "gear-center-distance" that is obtained by the use of the structure that is illustrated in dotted lines; namely, 30 the axle bracket seat 18 and the lips 16 and 17.

A further advantage of our present invention is that a single form of axle-bracket may be utilized in connection with a complete 35 line of motors having various "gear-center-distances", since the axle-bracket, in all cases, is associated with the same axle-bracket seat 5 and may be secured thereto in any suitable manner, as by rivets (not 40 shown) that extend through holes or openings 21 in the axle-bracket seat.

The end members or end-rings 6 and 7 are complementary in nature by reason of being associated with the opposite ends of the 45 motor frame and, consequently, it is deemed necessary to describe, in detail, only the end-ring 6, particularly, since the type of end-ring that is employed is not essential to our present invention, which is applicable to a 50 wide variety of motor frames.

The end-ring 6 is illustrated as being of a shallow cup shape having its flat outer 55 face provided with a central opening 22 that is adapted to receive any suitable type of armature bearing-housing, in accordance with customary practice. The edges of the opening 22 are preferably reinforced by a plate member 23 of triangular or other shape.

The end rings 6 and 7 may be secured to 60 the axle-bracket seat 5 in any suitable and convenient manner, but, inasmuch as such construction is immaterial to our present invention, no further description is deemed necessary here. The preferred arrangement 65 is set forth and claimed in a copend-

ing application of C. W. Starker and R. E. Hellmund, Serial No. 127,359, filed Oct. 24, 1916 (Case 5006).

However, in case the illustrated cup-shaped end-rings are adapted for direct riveting to the axle-bracket seats, a material saving in the number of different end-rings and manufacturing tools necessary for use in the production of a complete line of motors may be effected by forming depressions in 75 opposite sides of each end-ring that respectively correspond to the positions of the axle-bracket seats 5 and 18, or to any other selected two positions. The proper depression, as determined by the axle-bracket-seat 80 position, is presented to the seat and the ring is suitably secured thereto, as set forth in the above-identified patent.

The connecting members or tie-pieces 85 are preferably formed of pressed-steel and are provided with suitable ribs or bosses 24 for stiffening purposes. The tie-pieces are mechanically secured to the yoke member 1 and also to the end rings 6 and 7 through the agency of suitable rivets 25 or otherwise. 90 The tie-pieces just described form no part of our present invention except in so far as they perform a certain necessary function, and are fully set forth and claimed in Patent No. 1,198,080 granted to C. W. Starker and G. L. S. Kronfeld on September 12, 1916. The suspension bar 9 may also be of any suitable type to perform the intended 95 function of supporting the motor frame upon the truck (not shown) as is customary, and also to aid in mechanically connecting the yoke member 1 and the end-rings 6 and 7, as will be understood.

We do not wish to be restricted to the structural details or arrangement of parts herein set forth, as various modifications thereof may be effected without departing from the spirit and scope of our invention. We desire, therefore, that only such limitations shall be imposed as are indicated in the 100 appended claims.

We claim as our invention:

1. A magnetizable frame for inclosing the armature of a dynamo-electric machine comprising a yoke having a gap in one side provided with outwardly-extending axle-bracket-supporting lips of a length selected to procure a desired distance between the "center" of said frame and the axle-bracket 115 position.

2. An armature inclosing frame for dynamo-electric machines comprising a yoke having a gap in one side provided with outwardly turned axle-bracket-supporting lips, and a seat member bridging said lips to 125 magnetically and mechanically complete the periphery of the frame.

3. An inclosing frame member for dynamo-electric machines having a gap in one side provided with outwardly-turned lips of 130

a selected length, and a seat member bridging said lips, whereby the distance of the seat member from the "center" of said frame member is determined by the length of said 5 lips.

4. An inclosing frame member for dynamo-electric machines having a gap in one side provided with parallel-extending lips of a selected length, and an axle-bracket seat member secured to said lips, whereby the distance of the axle-bracket position from the "center" of said frame member is determined by the length of said lips.
- 10 5. An inclosing frame member for dynamo-electric machines having a gap in one side provided with parallel, outwardly-turned lips of a selected length, and a single axle-bracket seat member adapted to bridge said lips of whatever length, whereby a 20 single form of axle-bracket may be employed to procure a distance between the "center" of the frame member and the axle-bracket position that is determined by the selected length of said lips.
- 25 6. A frame for inclosing the armature of a dynamo-electric machine comprising a

magnetizable yoke having spaced end portions provided with axle-bracket-supporting lips of a length determined by the desired gear-center-distance dimension for said machine.

7. In the manufacture of a frame for a dynamo-electric machine, the method which comprises cutting a flat bar to a length determined by the gear-center distance of the 30 machine, forming the bar into a yoke member having spaced end portions, and attaching an axle-bracket seat member to the end portions of the yoke.

8. In the manufacture of a frame for a dynamo-electric machine, the method which comprises cutting and forming a flat bar into a yoke having spaced end projections of a length determined by the gear-center 35 distance of the machine, and attaching an axle-bracket seat member to the end portions of the yoke.

In testimony whereof, we have hereunto subscribed our names this 29 day of Sept., 1916.

RUDOLF E. HELLMUND.
CHARLES W. STARKER.
